By G. C. Kennedy,
Attorney.

UNITED STATES PATENT OFFICE.

JOHN M. SCHENK, DECEASED, LATE OF WATERLOO, IOWA, BY ELLA M. SCHENK,
ADMINISTRATRIX, OF WATERLOO, IOWA, ASSIGNOR TO ELLA M. SCHENK, OF
WATERLOO, IOWA.

CONCRETE LINTEL.

1,370,160.

Specification of Letters Patent. Patented Mar. 1, 1921.

Application filed April 22, 1920. Serial No. 375,828.

To all whom it may concern:

Be it known that I, ELLA M. SCHENK, a citizen of the United States of America, and a resident of Waterloo, Blackhawk county, Iowa, administratrix of the estate of JOHN M. SCHENK, deceased, late of Waterloo, Blackhawk county, Iowa, states that said JOHN M. SCHENK invented certain new and useful Improvements in Concrete 10 Lintels, of which the following is a specification.

This invention relates to concrete lintel blocks, and the object of the improvement herein is to provide a monolithic block suitably shaped for lightness and strength, reinforced to resist compression, and supplied with covering means adapted to prevent seepage of moisture into the hollow of the block or through the wall joint of the lintel 20 with the superincumbent wall structure.

This object has been accomplished by the means shown in the accompanying drawings, in which Figure 1 is a perspective view of spaced jambs with the improved lintel block, the covering means, and a portion of the superincumbent wall structure. Fig. 2 is a perspective view of the lintel block, with a portion broken away, and Fig. 3 is a perspective view of said covering means 30 therefor. Fig. 4 is a vertical longitudinal section of the lintel block, and Fig. 5 is a transverse section thereof.

Similar numerals of reference denote corresponding parts throughout the several 35 views.

The monolithic elongated concrete lintel block 1, having an upwardly opening elongated longitudinal closed-end hollow or trough 2, may be varied somewhat in its 40 form and dimensions without departing from this invention, but the specimen shown is an example of the work of a block molding machine, the subject of a co-pending application. This machine, in forming the 45 block, by means of a rotary former-head, trowels and shapes the trough 2 therein, whose end-walls 3 are arcuate conforming to the circumference of the former-head, and by eliminating interior angles at those 50 places, aids in strengthening the block by removing nodes of fracture.

The block is preferably reinforced against

compressive strains caused by its loading, and a rugged steel rod 4 may be embedded, or more than one, longitudinally in the lower 55 part of the block.

The numeral 5 denotes an elongated flat plate of metal or some substance impervious to water, of which one longitudinal edge part is flanged upwardly at 6, and the opposite longitudinal edge part is flanged downwardly at 7. The horizontal part of this plate is mounted coterminously upon the top of the block 1 so that the flange 7 abuts upon one side face of the block. 60 Superstructure blocks 8 may be laid upon this plate against the erect flange 6.

The depending flange part 7 should be on the side of the lintel most exposed to moisture, as the outside of a building, and prevents seepage or beating in of moisture or rain under the plate 5 and into the hollow 2 of the block. Any moisture which may permeate between the top of the plate 5 and the superincumbent structures will be prevented 70 from passing into the building by the erect flange 6. This affords a tight and secure 75 joint, as also an interlocking means between the lintel and the superstructure.

Having described this invention, what is 80 claimed is:

1. A concrete lintel-block having an elongated closed-end trough in its upper longitudinal face, and a plate positioned upon said block, having one longitudinal edge upwardly flanged.

2. A concrete lintel-block having an elongated closed-end trough in its upper longitudinal face, and an impervious plate positioned upon and covering said block, having 90 its opposite longitudinal edges flanged upwardly and downwardly respectively.

3. A lintel-block having a longitudinal trough in its upper face, and a plate impervious to moisture covering said trough 95 and having one longitudinal edge offset angularly at the abutting longitudinal angle of the block.

Signed at Waterloo, Iowa, this 29th day of March, 1920.

ELLA M. SCHENK,
Administratrix of the estate of John M.
Schenk, deceased.
